UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ATTACHMENT FOR SEWING MACHINES.

Application filed December 2, 1918. Serial No. 264,897.

To all whom it may concern:

Be it known that I, ALBERT H. DE VOE, a citizen of the United States, residing at Westfield, in the county of Union and State 5 of New Jersey, have invented certain new and useful Improvements in Attachments for Sewing Machines, of which the following is a specification, reference being had therein to the accompanying drawings.

10 This invention relates to sewing machines and particularly to attachments therefor by which an operator is enabled to stitch parallel with the edge of the work.

In applying facings to shirts or nether 15 garments, it has been found desirable to make a plurality of seams in successive operations at different distances from the edge of the work and thereafter to clear the work-support for the subsequent stitching of the lower 20 edge of the facing which in nether garments is usually irregular and curved along one edge.

The present invention aims to provide an 25 attachment in which the gauge proper may be quickly shifted to different positions relative to the line of seam-formation and to the cloth-plate or in other words may be quickly shifted to different positions effective and ineffective in directing the edge of work 30 relative to the needle.

The construction comprises an attachment 35 which may be in the form of an edge gauge having a blade portion, against which the edge of the work is adapted to travel, mounted on a carrier which is slidably supported beneath the cloth-plate for movement into either of two positions predetermined by stops or latches. The carrier may be swung a little about its support to disengage it 40 from one of the stops or latches to allow it to be moved into a position predetermined by the other stop. The edge gauge is shiftably supported on the carrier and is yieldingly sustained in an elevated position by a spring 45 socketed in the carrier permitting it to be depressed to an out of the way position, preferably flush with the cloth-plate, where it is detained by a latching lever whose operative end is accessibly presented at the 50 front of the machine for manipulation.

The invention is illustrated in the accompanying drawings in which Fig. 1 is a plan view of the cloth-plate of a machine with a portion thereof broken away to expose the

construction. Fig. 2 is a front elevation of 55 my device. Figs. 3 and 4 are opposite end elevations of the same, the latter being partly in section. Fig. 5 is a bottom plan view of the device partly in section. Fig. 6 is a horizontal cross-section on the plane of 60 line 6—6, Fig. 2, and Figs. 7, 8 and 9 represent successive stages in the stitching of a facing to a shirt.

The attachment is applicable to any type of lock or chain stitch machine but is illustrated as applied to a single needle chain-stitch machine of the Singer 110 class in which the looper L moves in a more or less vertical plane transverse the line of seam-formation. In the drawings 1 indicates the 70 cloth-plate which is secured by screws 1' to the frame of the machine and is recessed to receive the throat-plate 2 having an elongated needle-hole 2' for the needle 2" and slot 2'' for the feed-dog 3. The cloth-plate 75 is suitably cut away to provide openings for access to the lower stitch-forming instruments and these openings are closed by the cover slides 4 and 5, the latter of which is angularly notched as indicated at 6 to receive the fabric engaging element or gauge proper indicated by the numeral 7. The gauge is suitably secured to a pin or post 8, Fig. 4, slidably mounted in an aperture 9 of a carrier 10. In a socket 11 parallel with 85 the aperture is a coiled spring 12 which yieldingly urges the gauge upwardly and this spring normally holds the gauge in a position above the work-support in the plane in which the edge of the work travels and at 90 an elevation determined by the head or enlargement 13 on the lower end of the pin below the carrier.

To the under side of the carrier 10 a lever 14 is pivoted on a stud-screw 15, its rear end 95 being adapted to enter a notch 16 in the post 8 under the impulse of a coiled spring 17 pocketed in the horizontally extending socket 18 formed in a lug on the lower side of the carrier. The front end of the lever 100 14 is bent as indicated at 19 and 20 for convenience in manipulation and is preferably located below the cloth-plate. Preferably also the front end of the lever 14, i. e., the bent down portion 19, does not extend past 105 the curved front edge 21 of the cloth-plate so that there is no likelihood of the material being snagged thereupon.

The carrier 10 is of the irregular form shown in the drawings and is provided with an apertured boss or sleeve 22 which is laterally mounted on a rod 23 projecting laterally from a bracket 24 adjustably supported by the screw and slot connection indicated at 25—25' in the groove 26 in the base of the machine. The rod 23 extends transversely of the line of seam formation 10 and is substantially parallel to the work-support beneath which it is arranged. A second rod 27 is adjustably supported by the bracket 24 in parallelism with the first mentioned rod 23. About the rod 27 a 15 spring 28 is coiled with one end 29 inserted into a hole in the upper of two spaced jaws 30 extending from one side of the apertured boss or sleeve 22 and loosely embracing the rod 27 so as to permit a limited rotation 20 of the carrier on the rod 23. The coiled spring 28 urges the carrier laterally of the line of seam formation and also in a clockwise direction about the pin as viewed in end elevation Fig. 3. Projecting from a 25 pending ear 31 and in parallelism with the rods 23 and 27 is an abutment pin 32 having a collar 33 spaced close to the side wall of the ear 31. One side of the collar is beveled off as indicated to facilitate the 30 passage to a position to the left (Figs. 1 and 2) of the collar of a detaining member or latch in the form of a plate 35 which is secured by a screw 36 in a groove in an arm 38 depending from the carrier 10, the 35 plate having a beveled face cooperating with that of the collar 33. The abutment pin 32 and detent 35 limit rotation of the carrier 10 about the rod 23 in a clockwise direction and the upper one of the jaws 30 40 limits rotation of the carrier 10 about the rod 23 in a counter-clockwise direction. Obviously, however, the lower of the two jaws 30 could be made to limit the clockwise rotation of the carrier in order to take 45 the wear off of the plate 35 in the arm 38. A collar 40 is adjustably secured by the screw 41 to the rod 23 at a suitable distance from the face of the bracket 24 and determines one position of the carrier, the 50 other position being determined by the cooperating collar and detent 33 and 35.

The lever 14 serves not only as a latching mechanism to hold the gauge 7 depressed but also as an operating handle to shift the 55 gauge into either of its two positions. Pressure on the front end of the lever 14 in the direction of the arrow *a*, Fig. 1, will first release the gauge 7 to the action of its spring 12 whereupon it will rise above the 60 cloth-plate and continued pressure in the same direction will carry the rear end of the lever 14 against the left end of the lug in which the socket 18 is formed and thereafter the carrier will be bodily shifted to 65 the left until the detent 35 rises over and

behind the collar 33 as shown in Fig. 6 into a position holding the edge guide or gauge close to the needle.

The operation of the device is extremely simple. Supposing that the gauge occupies 70 an out of the way position substantially flush with the work-support, the operator may move the gauge to an elevated position above the work-support and at a short distance from the needle by merely striking 75 the accessible front end of the lever 14 a light sharp blow in the direction of the arrow *a* Figs. 1 and 2. To shift the gauge a greater distance from the needle in order to increase the depth of seam, the operator 80 merely strikes the accessible end of the lever 14 a light sharp blow in the direction of the arrow *b*, Figs. 3 and 4. In order to clear the cloth-plate for general stitching all the operator has to do is press the protruding gauge down flush with the cloth-plate, or nearly so, when the lever 14 functioning as a latch will detain it.

While the attachment is especially designed to facilitate the application of facings to shirts and nether garments, the successive stages in the formation of which are indicated diagrammatically in Figs. 7 to 9, inclusive, it will be understood that the invention is not limited to such use or manufacture. It will be obvious that instead of a single collar 33 the pin 32 may be provided with a plurality of similar collars. And while the spring 28 coiled about the 95 rod 27 is preferred as a means tending to 100 rotate the carrier 10 in a clockwise direction about the rod 23, other suitable means may be employed to automatically urge the carrier in a clockwise direction such as the force of gravity.

It is to be distinctly understood, however, that the invention is not limited to an edge-guide being obviously available for moving or shifting a binder, hemmer or other attachment and that the invention 110 contemplates such as being within its scope, the aforesaid attachments being broadly gauges, inasmuch as they direct work to the needle a predetermined distance in from the edge.

Having thus set forth the nature of the invention, what I claim herein is:—

1. An edge guiding device for sewing machines having a gauge for directing the edge of fabric, and said gauge being shiftable laterally of the line of seam formation and downwardly out of the plane in which the work travels whereby material may be directed with its edges in parallelism with the line of seam formation and stitched inward from its edges along a line not parallel therewith without stopping the operation of the stitch-forming mechanism.

2. In a sewing machine having a work support, an edge-guiding device comprising 120

- a gauge facilitating the making of seams parallel with the edge of the work, said gauge being shiftable laterally of the line of seam-formation and downwardly into the work support and upwardly into the plane in which the work travels whereby it may be rendered ineffective or effective and in the former case non-obtrusive.
3. In a sewing machine having a work-support, a member movably supported to one side of the plane of the work support, a primary stop against which the member is automatically urged to hold the same in a predetermined plane, secondary stops for holding the member at different distances from the line of seam formation, and a gauge sustained by the member in proximity to the work-support to enable the operator to guide the edge of the work being stitched a uniform distance from the needle.
4. An attachment for sewing machines having a work-support comprising a carrier, means urging the carrier laterally of the line of seam formation, an abutment, said carrier and abutment being urged together but being relatively movable in a direction transverse the work-support, stops for holding the carrier in predetermined positions, means for disengaging the carrier from one of the stops, and an edge gauge on said carrier normally sustained above the work-support in the path of the edge of the work.
5. An attachment for sewing machines having a work-support comprising an edge gauge, means supporting the gauge above the work-support but permitting displacement thereof to an out of the way position below the level of the work, means for holding the gauge in a plurality of positions at different distances laterally of the line of seam formation, and a common member through which the previously mentioned means are governed.
6. An attachment for sewing machines having a work-support comprising an edge gauge, a carrier on which said gauge is shiftable supported, a spring for shifting said edge gauge relative to said carrier, a latching mechanism for holding the gauge against the action of its spring, and latching mechanism for holding the carrier in a position with the gauge close to the line of seam formation, said carrier being movable laterally to locate the gauge farther from the line of seam formation.
7. In a sewing machine having a work-support, an attachment comprising a carrier fulcrumed beneath the work-support, a spring urging said carrier in the direction of the axis of its fulcrum, an arm on said carrier having a free end, a fixed member against which the arm is urged also by said spring, a stop on the fixed member confining the carrier in one position against movement by said spring in the direction of the axis of the fulcrum, a second stop limiting the carrier's movement in the direction of the axis of its fulcrum after it has been released from the first stop, a gauge on said carrier yieldingly urged by a spring to an elevated position above the work-support, said gauge being depressible from a position above the work-support to an out of the way position, and latching mechanism for holding the gauge depressed including a spring operated lever having a free end accessibly presented at the front of the machine, said lever also constituting means for shifting the gauge to its various positions.
8. An attachment for sewing machines having a work-support comprising a member movably supported below the work-support, means tending to hold the member in a predetermined plane, means for holding the member in different positions in said predetermined plane, means tending to move the member to a given one of said different positions, means for releasing the holding means, and a fabric guiding element sustained by the member.
9. An attachment for sewing machines having a work-support comprising a member movably supported below the work-support, means tending to hold the member in a predetermined plane, means for holding the member in different positions in said predetermined plane, and a fabric guiding element sustained by the member, said element being shiftable transverse the plane in which the member is normally held.
10. For sewing machines having a work-support, an edge-gauge, a carrier located below the work-support, means yieldingly supporting the gauge on the carrier, means supported by the carrier for detaining the gauge depressed, means normally urging the carrier in a direction transverse the line of seam-formation, and means for holding the carrier in any of a plurality of predetermined positions to space the gauge laterally different distances from the line of seam-formation.
11. An edge-guiding device for sewing machines having a work-support comprising a fabric engaging element sustained from beneath the work-support, a spring urging the element to an edge-guiding position above the work-support, and a latching mechanism automatically effective to detain the element in a non-effective edge-guiding position when depressed thereinto.
12. An edge-guide for sewing machines with a work-support comprising a fabric engaging element, a carrier, springs tending to hold said carrier in a predetermined position in a given plane and said element in an elevated position protruding above the work-support, and latching mechanism for holding said carrier in a second position in the given plane and said element

4
depressed in a non-effective edge-guiding position.

13. An edge-guide for sewing machines with a work-support comprising a fabric en-
gaging element, a carrier, springs, tending to hold said carrier in a predetermined position in a given plane and said element in an elevated position protruding above the work-support, latching mechanism for hold-
ing said carrier in a second position in the given plane and said element depressed in a non-effective edge-guiding position, said latching mechanism including a lever located below the work-support and having a manipulating free end terminating substantially at the front edge of the work-
support.

14. A guiding device for sewing machines

having a gauge to direct the work, means for holding the gauge in a plurality of posi- 20
tions in the plane of the work, means permitting displacement of the gauge below the plane of the work, and a common member through which the previously mentioned means are governed. 25

15. In a sewing machine, the combination with a work-support and stitch-forming mechanism including a needle, of a work-
guide adjustable laterally of the needle to various operative positions above the work-
support, said work-guide being shiftable to an inoperative position below the work.

In testimony whereof, I have signed my name to this specification.

ALBERT H. DE VOE.
